(57) CLAIM

The ornamental design for a handle for a BBQ set, as shown and described.

DESCRIPTION

FIG. 1 is a front perspective view of a handle for a BBQ set; FIG. 2 is a top view thereof;

FIG. 3 is a right side elevational view, of which the left side is a mirror image thereof;

FIG. 4 is a bottom view thereof;

FIG. 5 is a front view thereof; and,

FIG. 6 is a rear view thereof.

In the figures the dotted lines are structural features that are for illustrative purposes only and form no part of the claimed design.
